UNITED STATES PATENT OFFICE.

MONROE J. FERGUSON, OF WINTHROP, IOWA.

SLEIGH.

SPECIFICATION forming part of Letters Patent No. 278,326, dated May 29, 1883.

Application filed March 7, 1883. (No model.)

To all whom it may concern:

Be it known that I, MONROE J. FERGUSON, a citizen of the United States, residing at Winthrop, in the county of Buchanan and State of Iowa, have invented a new and useful Sleigh, of which the following is a specification, reference being had to the accompanying drawings.

This invention relates to sleighs, and has for its object to provide a sleigh possessing superior advantages in point of simplicity, durability, cheapness in manufacture, light weight, and general efficiency.

In the drawings, Figure 1 is a perspective view of my improved sleigh. Fig. 2 is a vertical longitudinal sectional view of the same. Fig. 3 is a transverse vertical sectional view taken through the cross-pieces and standards. Fig. 4 is a transverse vertical sectional view taken just in rear of the front curved ends of the runners.

Referring to the drawings, A A designate the runners of my improved sleigh, these being preferably formed of an iron rod that is rectangular in cross-section, which iron rod or bar can be provided with a steel shoe, or can be used without the latter, as desired. The runners A A are curved upward at their front ends, B, and are likewise curved upward at their rear ends, C, and from each of these ends the runner is turned inwardly to form an inwardly-extending horizontal support or extension, D E, respectively.

F designates the standards, each of which comprises an upright portion, G, having a flange or extension, H, at its bottom by which it is secured to the top edge of the runner, and an inwardly-projecting top portion forming a horizontal extension or support, I, as

shown. On these supports D, E, and I are placed the transverse beams J, to which the body of the sleigh is to be bolted or otherwise secured, these beams J being firmly fixed in position on the said supports. The supports E and I are braced by rods K, that extend from the inner ends of the supports down diagonally to the inner edge of the standards, and are secured firmly at their ends.

The standards are braced from displacement by rods L, that extend from the under side of their extensions that form the supports down diagonally to the top edge of the runners, and are also firmly secured at their ends.

The advantages of my invention are obvious. The construction is exceedingly simple and possesses great strength.

I claim as my invention—

As an improvement in sleds, the combination of the runners A A, curved upward at their front and rear ends, and having these ends B C turned inwardly to form supports D and E, the standards F, each formed of a single bar bent to form an upright inwardly-extending main portion, G, having the forwardly-projecting extension H at its bottom, and bent in at the top to form the extension I at right angles to the bottom extension, H, the transverse beams J, secured to the supports D E I, and the brace rods L, extending from under the top bent arm I of the standard down forward and inclined to the top edge of the runner, as set forth.

In testimony that I claim the foregoing as my own I have hereto affixed my signature in presence of two witnesses.

MONROE JEROME FERGUSON.
